(57) CLAIM

The ornamental design for a molded container, as shown and described.

DESCRIPTION

FIG. 1 is a perspective view of the molded container showing my new design;

FIG. 2 is a front view thereof;

FIG. 3 is a right side view thereof;

FIG. 4 is a left side view thereof;

FIG. 5 is a rear view thereof;

FIG. 6 is a top view thereof; and,

FIG. 7 is a bottom view thereof.

The broken lines depict portions of the molded container that form no part of the claimed design. The dot dash dot broken lines depict the boundaries of the claim and form no part thereof.

1 Claim, 7 Drawing Sheets
